DESIGN FOR A JUICE EXTRACTOR

Knight B. Lucas, Johnson County, Kans., and Joseph M. Majewski, Jr., Kansas City, Mo., assignors to John C. Hockery, Foster L. Talge, and Henry J. Talge, doing business as Rival Manufacturing Company, Kansas City, Mo.

Application October 2, 1944, Serial No. 115,558

Term of patent 14 years

(Cl. D89—1)

To all whom it may concern:

Be it known that we, Knight B. Lucas and Joseph M. Majewski, Jr., citizens of the United States, residing at Johnson County, State of Kansas, and Kansas City, in the county of Jackson and State of Missouri, have invented a new, original, and ornamental Design for a Juice Extractor, of which the following is a specification, reference being had to the accompanying drawing, forming part thereof, in which

Fig. 1 is a perspective view of a juice extractor, showing our new design,

Fig. 2 is a side elevational view thereof, and

Fig. 3 is a top plan view.

We claim:

The ornamental design for a juice extractor, substantially as shown.

KNIGHT B. LUCAS.
